UNITED STATES PATENT OFFICE.

BERRY SLUSHER, OF ROARK, KENTUCKY.

HAND-PLANTER.

1,270,665.

Specification of Letters Patent. Patented June 25, 1918.

Application filed September 20, 1917. Serial No. 192,357.

To all whom it may concern:

Be it known that I, BERRY SLUSHER, a citizen of the United States of America, residing at Roark, in the county of Leslie 5 and State of Kentucky, have invented new and useful Improvements in Hand-Planters, of which the following is a specification.

The invention relates to improvements in hand planters for corn and similar substances and its principal object is to provide 10 a device of this character by means of which two different substances may be planted at the same time.

Another object of the invention is to provide 15 a receptacle for the substances to be planted, which receptacle is divided into two compartments with means for converting the two into one large compartment that may be used when only one substance is to 20 be planted.

Still another object of the invention is to provide in a device of this kind regulating means whereby a specified number of grains may be planted.

25 Still another object of the invention is to provide a hand planter which may be easily and cheaply made, which will be effective and durable in proportion and which can be placed on the market at a low price.

30 Other and further objects will appear as the device is set forth in detail in the description which follows. To the specified embodiment in which it is shown in the drawings the invention is not to be restricted. The actual reduction to practice 35 may suggest certain desirable alterations or changes and these the right is reserved to make provided they do not depart from the spirit of the appended claims.

40 In the accompanying drawings:

Figure 1 is a longitudinal sectional view of the invention.

Fig. 2 is a section on the line 2—2 of Fig. 1.

45 Fig. 3 is a section on the line 3—3 of Fig. 2.

Fig. 4 is a perspective view of the grain-ejecting plate.

50 Fig. 5 is a section on the line 5—5 of Fig. 4.

In detail the device consists of a wedge-shaped member 1 which is hollow on the interior and whose ends are provided with the triangular openings 2. The plate 3 is 55 rigidly connected to the wedge-shaped member 1 on one of its sides, while a plate 4 is

hingedly connected to this member on the other of its sides, as indicated by 5. Both the plates 3 and 4 have attached to them, in any suitable manner on their outer faces 60 at their upper ends, the handles 6.

The receptacle 7 is suitably attached on the outer face of the plate 3, this receptacle having three walls of its own, the plate acting as a fourth wall. This receptacle is 65 suitably covered by a lid 8 hingedly attached to the plate 3. A partition 9 divides the receptacle 7 longitudinally into two compartments which, for practical purposes, it is found best to arrange in two different 70 sizes. Therefore, the partition 9 divides the receptacle into compartments 10 and 11 which are of different capacities. The partition 9 is slidably supported in the receptacle 7 between beads 12 which are suitably 75 attached one pair on the plate 3 and one pair on the front wall of the receptacle, both pairs being interior to the receptacle.

A gate 13 is hingedly attached on the bottom of the receptacle 7, so that when it 80 stands vertically the partition 9 will rest upon its free end and the partition 9 is provided at its bottom end with a pivotally mounted U-shaped catch which straddles the free end of the gate 13. This U-shaped 85 catch comprises the members 14 which are rigidly attached to the stud 15 after the latter has been inserted through the partition 9 in which it has pivotal movement.

A grain-ejecting plate 16 is pivotally supported at one end on a rod 17 which is suitably held between two ears 18 attached on the inner face of the plate 4. The plate 16 is divided for the greater part of its length so that it may project into the receptacle 7 90 on either side of the gate 13. Thus one portion of the plate 16 projects into the compartment 11 and the other portion projects into the compartment 10. The plate 3 is provided with transverse slots to permit the 95 divided portion of the plate 16 to pass through it into the receptacle 17 and the bottom 19 of the latter is depressed at certain portions to permit the plate 16 to lie flush with the bottom when inserted its full 100 distance into the receptacle 7.

Apertures 20 are formed in the plate 16 in the divided end thereof, the narrower leg of this divided end having a small aperture. On the bottom face of the plate 16 and set 110 into the latter so that they lie flush therewith are plates 21. These plates are

held in position by flat head screws 22 which pass through body holes formed in them and screw into any one of the threaded holes 23 formed in the plate 16. The plates 21 are intended as adjusting means for varying the areas of the apertures 20, and therefore, their convex ends are generated to the same radii as the radii of the apertures 20. Thus the screws 22 may be made to engage different holes of the holes 23 to so position the plates 21 that the areas of the apertures 20 may be varied. Connecting with the top of the wedge-shaped member 1 and with the longitudinal edges of the plates 3 and 4, there are flexible pieces 24 composed of either leather or some suitable fabric, these pieces being long enough to extend up the plates 3 and 4 to a point above where the plate 16 is attached. The object of these flexible pieces is to permit the free movement of the plates toward or from each other which is necessary to effect the operation of the planter.

In operation, the compartments 10 and 25 are filled with two different substances to be planted. It is presumed that these two substances are corn and beans since it is common for farmers to plant these two together to allow the corn stalk to act as a pole on which the bean vines may climb. As the plates 3 and 4 are oscillated the grains of the two substances drop down into the apertures 20 and when the two plates 3 and 4 have been moved the extreme distances 35 from each other the apertures 20 are withdrawn from the receptacle 7 and the grains which have previously fallen into the apertures 20 are permitted to drop down between the plates 3 and 4 and to pass out the open ends of the wedge-shaped member 1, this latter having previously been inserted in the ground when the plates 3 and 4 were close together.

The areas of the apertures 20 may be varied as before explained, to permit the dropping of a specified number of grains in planting. In the event that it is desired to plant only one substance, the U-shaped catch previously referred to may be disengaged from the free end of the gate 13, permitting the latter to swing either to one side or the other of the receptacle as shown in dotted lines in Fig. 2. The swinging of this

gate to one side of the receptacle renders inoperative one of the apertures 20 and directs the substance being planted to the remaining aperture 20. In using the device for planting only one substance, there is no need for the partition 9 and it may be withdrawn from between the beads 12.

The invention having been set forth what is claimed as new and useful is:

1. A hand planter comprising a wedge-shaped member having openings at either end, a pair of plates attached to this member, one rigidly connected therewith and the other having hinged connection, a receptacle carried by the rigidly connected plate, a grain-ejecting plate having pivotal connection with the hingedly connected plate, the grain-ejecting plate entering the receptacle and being provided with apertures by means of which the grain is withdrawn from the latter and dropped into the wedge-shaped member, and flexible pieces attached to the wedge-shaped member and to the edges of the plates and extending to a point above that at which the grain-ejecting plate is connected.

2. The combination in a hand planter of a pair of oscillatory plates conjoined at their lower ends and having means for receiving between them and discharging therefrom a substance to be planted, a receptacle attached to one of said plates, a partition member removably secured in the receptacle, a swinging gate hingedly attached to the bottom of the receptacle and secured in a vertical position by the partition member, and a grain-ejecting plate pivotally connected with the other of said oscillatory plates, said grain-ejecting plates slidably entering the receptacle and having a divided end, whereby one of said divisions will enter the receptacle on either side of said gate, each of the said divisions being provided with an aperture by means of which substances being planted may be withdrawn from the receptacle on either side of the partition member and of the gate, said gate being adapted to swing to either side of the receptacle whereby one of the divisions of the grain-ejecting plate is rendered inoperative.

In testimony whereof I affix my signature. 105
BERRY SLUSHER.
